UNITED STATES PATENT OFFICE.

WADE H. HORN, OF FLINT, AND HENRY D. SMALL, OF DEARBORN, MICHIGAN.

REFRIGERATING APPARATUS.

Application filed June 18, 1925. Serial No. 38,029.

This invention relates to a refrigerating process and apparatus therefor, and has for its object to provide, in a manner as hereinafter set forth, a refrigerating process and apparatus whereby refrigeration is obtained through the medium of ventilation and washed air.

A further object of the invention is to provide, in a manner as hereinafter set forth, 10 a refrigerating process and apparatus whereby excessive shrinkage, as well as the accumulation of ice in the bunkers is eliminated.

A further object of the invention is to provide, in a manner as hereinafter set forth, 15 a refrigerating process and apparatus whereby the air in a chilled or storage room can be continuously freshened during the operation of refrigeration, in accordance with this invention, under such conditions materially 20 lessening the contamination of the air in such room to overcome any material reduction in its refrigerating action.

Further objects of the invention are to provide, in a manner as hereinafter set forth, 25 a process of refrigeration and means for carrying out the process and with such means comparatively simple in its construction and arrangement, strong, durable, thoroughly efficient in use, readily installed and 30 comparatively inexpensive.

With the foregoing and other objects in view, the invention consists of the new, novel and improved method of refrigeration, as well as the apparatus for carrying out the 35 process, as hereinafter more specifically described and illustrated in the accompanying drawings, wherein is shown an embodiment of the invention, but it is to be understood that changes, variations and modifications 40 with respect to the apparatus shown falling within the scope of the claims hereunto appended can be had.

In the drawings, like reference characters 45 denote corresponding parts throughout the several views, and in which:—

Figure 1, is a fragmentary view, in cross section of a compartment structure or building, showing the arrangement therewith of the elements of a refrigerating apparatus in 50 accordance with this invention.

Figure 2, is a like view taken at right angles to Figure 1.

Figure 3, is a top plan view partly in section and broken away.

Figure 4, is an enlarged fragmentary view in cross section.

The drawings illustrate, by way of example, the adaptation of a refrigerating apparatus in accordance with this invention with respect to a chill room and a storage room, 60 but with the elements of the apparatus shown generally and not specifically with respect to the storage room, however the specific construction and arrangement of the elements of the apparatus are shown specifically with respect to the chill room.

In the drawings, 1 denotes conventionally a compartment structure or building provided with a basement 2, a chill or refrigerated room 3, a refrigerant or refrigerating 70 apparatus receiving compartment 4 arranged at the top of a chill room 3, a storage room 5, a refrigerating apparatus receiving compartment 6, arranged at the top of the storage room 5, ventilators 7 opening into 75 the top of the compartment 4 and ventilators 8 opening into the top of the compartment 6. The chill room 3 has its walls, top and bottom insulated throughout through the medium of an insulation body of cork, as indicated at 9, and this arrangement also applies to the storage room 5. The chill room 3 communicates with the compartment 4 in a manner to be presently referred to. The ventilators 7 or 8 provide two functions, 80 in that the air passes upwardly from the refrigerating space, after which the lighter of such air escapes through the ventilators 7 or 8, and the heavier or fresher of such air is acted upon by the refrigerant discharged 90 from the pipes 25 and returned to the chill room 3. The foul air that escapes through the ventilators 7 or 8 is replaced by a fresher or heavier air coming through the ventilators 7 or 8. The ventilators 7 or 8 afford a 95 means for the foul air to escape and for the same to be replaced by fresh air entering through the same.

The compartment 4, as well as the compartment 6, is provided through the medium of a centrally disposed transversely extending beam 10 upon which is mounted a series of longitudinally extending beams or joists 11, arranged in spaced relation and further spaced from the side walls of the compartment. The outer beams of the series of beams 11 are indicated at 12, 12 and which are spaced from the side walls of the compartment to provide vertically disposed air passages whereby the light or warm air from the chill room, or from the storage room, will pass into the compartment 4, or 6, 100 105 110

As the elements of the apparatus arranged in the compartment 4, are the same as that arranged in the compartment 6, the process, and apparatus for carrying the process out, 5 will be described with respect to the chill room 3 and compartment 4 and such description is to be understood as to also apply to the storage room 5 and compartment 6.

Arranged within the compartment 4 and 10 supported by the series of beams 11 is a pair of oppositely disposed spaced bunkers each including a vertically disposed side wall 13 and a downwardly inclined floor 14 and with the inclination of the floor 14 extending 15 towards the longitudinal center of the compartment 4. The side walls 13 of the bunkers extend from one end to the other end of the compartment and said side walls 13, as well as the bottoms 14, of the bunkers, have 20 arranged therein, as well as throughout, a body of insulation, preferably formed of cork, and indicated at 15. The floors 14 extend at opposite inclinations with respect to each other and further each has its inner 25 end terminate at one side of the longitudinal center of the compartment 4. Each of the bunkers include a plurality of supports 16 which are interposed between the bottom 14 and the series of beams 11, and the side wall 30 13, of each bunker, forms in connection with the side walls of the compartment 4 a continuation of the air passage 15' and the latter terminates at its upper end at a point removed from the top of the compartment 4, 35 due to the fact that the side walls 13 of the bunkers do not extend to the said top.

Extending longitudinally of the compartment 4 is a pair of spaced brine tanks 17, 18, which are arranged over the floors 14, as 40 well as being spaced therefrom and from the walls 13. Arranged in the tank 17, as well as the tank 18, is a refrigerant coil 19 and which is of sufficient capacity to chill the sodium chloride brine circulating through 45 tanks 17 and 18 to the temperature necessary to chill the air that is washed or passes through the dripping sodium chloride brine discharged from the tanks 17 and 18 through a means to be presently referred to. The 50 refrigerant can be supplied to the coils 19 in any suitable manner.

Connected to the tanks 17 and 18 and extending transversely of the compartment 4 is a header 20 for one end of a longitudinally extending set of discharge pipes 21, and connected to the other end of the tanks 17 and 18 and extending transversely of the compartment 4 is a header 22 for the other end of the series of discharge pipes 21. The 55 construction of the header is better shown in Figure 4 and it is formed of a series of pipe branches 23 connected together by inverted T-couplings 24, and to the vertical leg of each of which is connected a vertically disposed pipe branch 25 connected by a cou-

pling 27 to one end of a discharge pipe 21 and each of the latter is provided substantially throughout, at its top, with a lengthwise extending discharge slot 28.

Each header, has depending from each end 70 thereof, a vertically disposed pipe branch 29 which opens into an angle-shaped feed pipe 30 connected to an end of a brine tank. The feed pipes 30 are arranged at the lower portion of the ends of the brine tanks and extend inwardly therefrom for the purpose of supporting, in connection with the pipe branches 29, the headers above the bottoms of the brine tanks and further in spaced relation with respect to the inner sides of 80 said tanks.

The vertical pipe branches 25 of each header are arranged in spaced relation and the pipe branches 25, of one header, are positioned in parallelism with respect to the pipe branches of the other header and each pair of parallel pipe branches 25 have arranged therebetween a longitudinally extending flat substantially narrow, rough board 31 which constitutes a deflector for the brine as it is 90 discharged or overflows from the pipe 27. The boards 31 are arranged against the pipes 27 and are connected therewith in any suitable manner and are of a length slightly less than the length of said pipes, but the 95 boards 31 are of greater width than the diameter of the pipes 27 whereby, when the boards 31 are mounted in position they will project laterally from each side of the said pipes 27. The boards 31 are positioned in 100 sidewise arrangement, but spaced from each other.

Extending transversely of the compartment 4 and arranged over, as well as being spaced from the pipes 27, is a feed pipe 32 105 for supplying the brine to the tanks 17 and 18 and for such purpose one end of the pipe 32 opens into a valved inlet pipe 33 which communicates with the tank 17, through the top thereof. Leading from the pipe 32 and 110 communicating with the tank 18, through the top thereof, is a valved inlet pipe 34. The pipe 32 opens into a supply pipe 35 which extends into the basement 2 and communicates with a pump 36 which is employed 115 for pumping the brine from a reservoir or tank 37 arranged within the basement 2 and said reservoir or tank 37 has leading thereto a conducting pipe 38 for the discharge of the overflowing brine from the 120 pipes 27.

Secured to the inner end of each of the bunker floors 14 is a longitudinally extending collecting trough 39 and bridging the space formed between the troughs 39 and 125 disposed centrally with respect to the series of pipes 27 is an inverted V-shaped deflector of the louvre type and which is indicated at 40, and with the sections thereof disposed at a downward inclination. The lower sec-

tions 41 of the deflector 40 extend over the top edges of the opposed sides of the troughs 39.

Arranged below and connecting the troughs 39 is a discharge pipe 42 with which communicates the conducting pipe 38 leading to the reservoir or tank 37.

The sodium chloride brine is circulated by the pump 36 through the tanks 17 and 18 and flows from said tanks into the headers, from there into the slotted pipes 27 and overflows on to the rough boards 31, thence dripping from the rough boards 31 on to the insulated bunker floors 14 and flows into the collecting trough 39 and from which the brine is discharged by the pipe 42 into the pipe 38 which leads to the tank or reservoir 37. As the brine drips from the board 31 it will wash and cool the air and the cool air will flow through the louvre deflector 40 into the chill room 3. The air in the room will take on heat and rise to the bottom of the bunker floors 14, thence to passages 14' from there to the ventilators 7, which will permit the lighter air to escape, under such conditions causing the air in the chill room to be freshened and less contaminated. The air that passes the ventilators will be drawn into the dripping brine and will pass through the course as aforesaid and by the foregoing operation refrigeration is obtained by a ventilated and washed air process. The foul air which has escaped through the ventilators 7 or 8 is replaced by fresh air entering through the same, as hereinbefore set forth.

It is thought the many advantages, by the process of refrigeration and apparatus therefor, in accordance with this invention, can be readily understood and although the preferred embodiment of the apparatus is as described in the claims, yet it is to be understood that the changes in the details of construction can be had which will fall within the scope of the invention as claimed.

What we claim is:—

1. A refrigerating apparatus comprising a set of refrigerant conducting pipes having means to provide for the discharge of the refrigerant therefrom to act on air directed thereunder to a refrigerated space, ventilators positioned above said pipes for the refrigerated space, a pair of spaced oppositely inclined opposed bunkers arranged below and receiving the discharge from certain of said pipes, a louvre positioned below receiving the discharge from the other of said pipes, bridging the space between said bunkers and through which passes the air on its travel to said refrigerated space, after being acted upon by the refrigerant, the said means consisting of lengthwise extending slots formed in the top of said pipes, and

means opening into each end of said pipes for supplying the refrigerant thereto. 65

2. A refrigerating apparatus comprising a set of refrigerant conducting pipes having means to provide for the discharge of the refrigerant therefrom to act on air directed thereunder to a refrigerated space, ventilators positioned above said pipes for the refrigerated space, a pair of spaced oppositely inclined opposed bunkers arranged below and receiving the discharge from certain of said pipes, a louvre positioned below receiving the discharge from the other of said pipes, bridging the space between said bunkers and through which passes the air on its travel to said refrigerated space, after being acted upon by the refrigerant, a pair 70 of headers, each common to and opening into one end of said pipes, and means for supplying the refrigerant to said headers. 75

3. A refrigerating apparatus comprising a set of refrigerant conducting pipes having means to provide for the discharge of the refrigerant therefrom to act on air directed thereunder to a refrigerated space, ventilators positioned above said pipes for the refrigerated space, a pair of spaced oppositely inclined opposed bunkers arranged below and receiving the discharge from certain of said pipes, a louvre positioned below receiving the discharge from the other of said pipes, bridging the space between said bunkers and through which passes the air on its travel to said refrigerated space after being acted upon by the refrigerant, the said means consisting of lengthwise extending slots formed in the top of said pipes, and a pair of headers, each common to and opening into one end of said pipes, and means for supplying the refrigerant to said headers. 90

4. A refrigerating apparatus comprising a set of refrigerant conducting pipes having means to provide for the discharge of the refrigerant therefrom to act on air directed thereunder to a refrigerated space, ventilators positioned above said pipes for the refrigerated space, a pair of spaced oppositely inclined opposed bunkers arranged below and receiving the discharge from certain of said pipes, a louvre positioned below receiving the discharge from the other of said pipes, bridging the space between said bunkers and through which passes the air on its travel to said refrigerated space after being acted upon by the refrigerant, and a deflector positioned against and extending lengthwise of the bottom of each of said pipes. 115

In testimony whereof, we affix our signatures hereto.

WADE H. HORN.
HENRY D. SMALL.
